UNITED STATES PATENT OFFICE.

WILLIAM E. DENIS, OF NEW HAVEN, CONNECTICUT.

REPEATING DRIP-PAN ALARM.

Application filed October 12, 1922. Serial No. 504,212.

To all whom it may concern:

Be it known that I, WILLIAM E. DENIS, a citizen of the United States, residing at New Haven, in the county of New Haven and 5 State of Connecticut, have invented certain new and useful Improvements in Repeating Drip-Pan Alarms; and I do declare the following to be a full, clear, and exact description of the invention, such as will enable 10 others skilled in the art to which it appertains to make and use the same.

My invention relates to improvements in alarms or annunciators for use to give a signal of some sort when a liquid level rises 15 beyond a predetermined extent, the present embodiment of the invention being devoted more particularly to a device intended primarily for use in connection with the drip pans of refrigerators.

One object of the invention is to provide 20 a device of the character set forth which will repeatedly sound an audible alarm when the drip pan should be emptied.

A further object is to provide an extremely 25 simple and inexpensive, yet a highly efficient and reliable construction which may readily be set within an ordinary drip pan, the device being preferably weighted so that it will remain in position within the pan, 30 without the necessity of attaching it thereto, although in some instances attachment may be effected if desired.

With the foregoing in view, the invention resides in the novel subject matter herein- 35 after described and claimed, the description being supplemented by the accompanying drawings.

Figure 1 is a side elevation partly in section showing the alarm set for operation.

Figure 2 is a duplicate of a portion of Fig. 1, illustrating the manner of setting the alarm.

Figure 3 is a horizontal section on line 3—3' of Fig. 2.

In the drawings above briefly described, the numeral 1 designates a standard whose lower end is here shown as provided with a weighted base 2 adapted to rest upon the bottom of a drip pan. It will be understood 50 however that in some instances the standard might well be secured to the bottom of the pan, but it is preferable, in order that an article may be had which may be sold and merely set in place by the purchaser, that

the device, whether formed of wood or 55 metal, or from a combination of the two, shall be sufficiently heavy to remain in place upon the pan bottom.

In the present showing, the standard 1 is provided with a pair of opposed lower arms 60 3 and with a pair of opposed upper arms 4, the two arms 3 being in alignment with each other while the arms 4 are laterally offset from each other in order to clear a pair of spring arms 5 which 65 rise from the arms 3. The upper ends of the arms 5 are provided with clappers 6 adapted to successively strike a gong 7 which is mounted on the upper end of the standard 1. 70

For tensioning the arms 5 and successively releasing said arms, I have provided a pair of vertically swinging arms 8 which are fulcrumed to the arms 4 as indicated at 9. The lower ends of the arms 8 are provided with 75 floats 10 while the upper ends of said arms which extend above the fulcrums 9, force inwardly upon pins 11 carried by the clappers 6, when the arms 8 rise under the influence of the floats 10. Any suitable provision is 80 made whereby the arms 8, after tensioning the springs 5, will successively release them so as to give two alarm signals when the drip pan should be emptied. In the present showing, one of the arms 8 is longer than 85 the other and this is preferable, but it will be understood that the same end could be obtained in other ways.

After the device has operated and the drip pan has been emptied, in order to reset the device, it is simply necessary to push simultaneously inward upon the two spring arms 5, as indicated in Fig. 2. Thus, the pins 11 swing the arms 8 inwardly until said pins can pass over the upper extremities of said arms in condition to engage the inner sides thereof. The spring arms 5 are then released and assume a substantially vertically position but as the water level rises, said arms swing upwardly as indicated in Fig. 1, to place the arms 5 under tension and to release them successively when the water level has reached the point at which the pan should be emptied. 160

Since excellent results have been obtained by the details disclosed, they are preferably followed, but within the scope of the invention as claimed numerous minor changes 105

may of course be made and it will be understood that any desired materials may be used in manufacture of the device.

I claim:

- 5 1. An alarm of the class described comprising a base, an integral standard rising therefrom, a signal secured to the upper end of the standard, a spring arm secured at its lower end to the standard, said arm extending in vertical spaced parallelism with respect to the standard and having its upper end terminating adjacent the signal, an impact element secured to said upper end to strike it, and a float carrying arm pivotally connected to the standard and having its upper free end engaged with the impact element to place said spring arm under tension as the liquid level rises.
- 10 2. A liquid level annunciator comprising a standard having opposed upper arms, opposed lower arms, a gong mounted on the upper end of said standard, a pair of spring arms rising from said lower arms and hav-

ing gong operating clappers, and a pair of float operated arms pivoted to said upper arms for tensioning said spring arms, provision being made for successively releasing said spring arms.

3. A liquid level annunciator comprising a base, a standard rising therefrom, a pair of extensions projecting at right angles from the standard, a bell secured to the upper end of the standard, a pair of spring arms secured at their lower ends to the latter, the upper ends of said arms being arranged beneath the bell, hammers secured to the last named ends of the arms for striking the bell, stop pins projecting from the hammers, and a pair of float-actuated arms pivoted between their ends on the aforesaid extensions, the upper free ends of the last named arms being releasably engaged with said stop pins.

In testimony whereof I have hereunto affixed my signature.

WILLIAM E. DENIS.
